UNITED STATES PATENT OFFICE.

BENJAMIN S. DEAN, OF PHILADELPHIA, PENNSYLVANIA.

MASSAGE DEVICE.

No. 831,711.

Specification of Letters Patent.

Patented Sept. 25, 1906.

Application filed October 21, 1905. Serial No. 283,748.

To all whom it may concern:

Be it known that I, BENJAMIN S. DEAN, a citizen of the United States of America, and a resident of Philadelphia, county of Philadelphia, State of Pennsylvania, have invented certain new and useful Improvements in Massage Devices, of which the following is a specification, reference being had to the accompanying drawings, forming a part thereof.

My invention relates to improvements in massage devices, and particularly to mechanical means for grasping the flesh and working or kneading it.

Most forms of mechanical massage devices are mere vibrating means for lightly pounding the flesh or roller devices for merely rolling over the flesh. In hand manipulation of flesh for massage purposes it is common to take up a piece of flesh between the thumb and the finger and work or knead the flesh by working the thumb and finger backward and forward.

It is the main object of my present invention to produce a machine which shall as closely as possible imitate this hand manipulation of the flesh; and to this end I provide a plurality of massage members for grasping the flesh and means for so operating the members as to knead or work the flesh between them.

In the preferred form of my invention the grasping members are rollers which rotate slowly in a direction toward each other, so as to pick up and hold the flesh, and I provide means for imparting contravibrating movements to the said rollers while they are rotating, these contravibrating movements being very rapid relatively to the movement of rotation thereof and being through but a small arc of a circle. In a machine which I have designed for this purpose and in which my invention is embodied the rollers rotate toward each other at about the speed of one hundred revolutions to the minute, while oscillatory movements are simultaneously imparted thereto through one-eighth of a revolution two thousand times a minute, the said oscillations being in directions opposite to each other.

My invention also consists in many novel combinations of parts and features of construction, which I will point out more clearly hereinafter, and in order that my invention may be fully understood I will describe in detail an embodiment thereof and will then point out the novel features in claims.

In the drawings, Figure 1 is a view in longitudinal section through a device embodying my invention, the plane of section being taken substantially upon the line 1 1 of Fig. 60. Fig. 2 is a view in transverse section thereon, the plane of section being substantially upon the line 2 2 of Fig. 1. Fig. 3 is an end view of the device. Fig. 4 is a detail view showing a portion of a gear-wheel with 65 its hub and a cam-slot therein, the same being a portion of the mechanism for transmitting the vibrating movements above referred to. Fig. 5 is a fragmentary view showing particularly the slotted condition of 70 the box or housing which permits lateral movements of the massage-roller shafts. Fig. 6 is a fragmentary view of one of the massage-roller shafts.

The views are drawn to an exaggerated 75 scale in order to better illustrate the device, the device itself being considerably smaller than the device as illustrated.

The massage members in the device herein comprise rollers 5 and 6, mounted upon 80 shafts 7 and 8, carried by arms 9 and 10, connected to sleeves 11 and 12. The sleeves 11 and 12 are mounted upon a stationary arbor 13, secured to and carried by a box or frame 14. The sleeves 11 and 12 are mounted loosely 85 upon the said arbor, whereby the rollers 5 and 6, carried by the arms 9 and 10 secured thereto, may move freely backward and forward toward and away from each other. Springs 15 tend to press the said rollers with 90 a yielding pressure toward each other, but permit the said rollers to be forced apart against such yielding pressure.

The box or frame-support 14 is provided with a handle 16, by which the device as a 95 whole may be conveniently manipulated, and a drive-shaft 17 passes through the said handle from the exterior thereof to the interior of the said box. This shaft may be driven by any suitable means—as, for instance, by a 100 flexible shaft connection with a motor of any kind. At its end within the box the said shaft is provided with a drive-pinion 18, which engages a spur-gear 19, loosely mounted upon the stationary arbor 13. This gear 105 conveniently has a long hub, so that it may have a long bearing on the said arbor, and the said hub is also employed for the purpose of supporting another gear-wheel 20, which is rigidly fastened thereto. The said 110 gear-wheel 20 takes in with a spur-gear 21 upon the shaft 7, which carries the roller 5.

The shaft 7 penetrates to the interior of the box for this purpose, and the said box is conveniently slotted, as shown in Fig. 5, where the shaft so penetrates it, in order to permit the swinging movement of the shaft above referred to. Rotation of the shaft 17 then will impart a continuous rotary movement to the said roller 5. The spur-gear 19 has secured to the face thereof bevel gear-teeth 22, which intermesh with a bevel gear-pinion 23, arranged to rotate upon a stationary stud at right angles to the axis of the arbor 13, the beveled gear-wheel 23 also intermeshing with another beveled gear-wheel 24, mounted to turn loosely upon the hub of the spur-gear 19. The gear-wheel 24 will itself then rotate in a direction opposite to the rotation of the spur-gear 19, and a gear-wheel 25, (corresponding to the gear-wheel 20,) which is affixed to the said beveled gear-wheel 24, will rotate with it in a direction opposite to the direction of the said gear-wheel 20. The gear-wheel 25 intermeshes with a spur-gear 26, carried by the shaft 8, which carries the rollers 6, and movements of rotation will hence be imparted to the shaft 8 and roller 6 opposite to the movements imparted to the roller 5 and shaft 7, as shown by the arrows in Figs. 2 and 3. It will be understood, of course, that the box 14 is also slotted where the shaft 8 enters it, the same as above described in connection with the shaft 7. Noting the direction of the arrows in Fig. 3, it will be seen that the rollers turn toward each other, and the ratio of the gearing is so designed that the speed of such rotation shall be about one hundred times a minute. If these rollers be applied to the flesh, the tendency thereof will be to draw the flesh up between them, the rollers slightly parting to permit the flesh to pass between them without unduly pinching same.

I will now describe the means for imparting the vibrating movements to the rollers, such movements being, it will be remembered, preferably in opposite directions through short arcs and at a high rate of speed. The drive-shaft 17 is provided with a cam 27 in the form of an oblique disk, as shown, said cam engaging with a projection 28, formed at the lower end of a swinging frame 29, said frame being pivotally hung upon a bar 30, secured transversely within the box 14. Both of the gear-wheels 21 and 26 are provided with long hubs, and upon each of the said hubs is mounted a collar 31. These collars 31 have flanges 32, which are engaged by projections 33 of the said frame 29, whereby the said collars 31 are vibrated backward and forward by the said frame in its vibration, the said frame being itself vibrated by the cam 27, as above set forth. Each of the said collars 31 is provided with a pin 34, which passes through a slot 35, with which each of the said hubs is provided, and through a slot

36, (see particularly Fig. 6,) with which each of the shafts 7 and 8 is provided. The slots in the said shafts are in line with their axes, but the slots 35 in the hubs of the gears 21 and 26 are oblique. One of the said hubs, with its slot 25, is shown in detail, Fig. 4, and the corresponding slot for the hub of the other of the said wheels will be similar thereto, except that it will preferably be oblique in the opposite direction. The reciprocating movements of the collars 31 will by reason of the pin-and-slot connection just described impart relative movements of progression and retrogression between the shafts and the spur-gears thereon, such movements constituting the vibrating movements above referred to. The slots 35 are here shown as extending through about one-eighth of a complete revolution, so that the vibrating movements will be movements through an arc of about one-eighth of a circle, and the said slots being in opposite directions the said vibrating movements will be opposite movements of vibration or oscillation of the two shafts and rollers with respect to each other. The shaft 17 is arranged to revolve at a very high rate of speed, the same being geared down considerably through pinion 18, spur-gear 19, and gear-wheels 20 25 to spur-gears 21 26, so that such a high rate of speed of the drive-shaft will only effect a comparatively low rate of speed of the rollers 5 and 6. The cam 27, however, being mounted directly upon the drive-shaft, the speed of the vibrating movements will be very high, and in the machine so shown the speed of such vibration is arranged at about two thousand per minute when the rollers revolve at about one hundred revolutions per minute. A device so constructed will produce a massaging effect closely imitating the hand massage, the slow rotation of the rollers causing the same to continuously grasp the flesh when applied thereto, while the reciprocating or vibrating movements thereof knead or work the flesh in the most approved manner.

It will be obvious that the foregoing is but one embodiment of my invention and that the same is capable of many and varied modifications within the spirit and scope of my invention, and, further, that certain parts may be employed in connection with other parts of different construction. Hence I do not desire to be limited only to the precise details of construction and combination of parts herein.

What I claim is—

1. In a massage device, the combination with a pair of massage-rollers for engaging the flesh, of means for rotating the rollers in opposite directions whereby adjacent surfaces of the said rollers will move in the same direction.
2. In a massage device, the combination with a plurality of massage-rollers movable

as a whole toward and away from each other, and arranged to operate upon flesh engaged between them, of means for imparting vibratory movements to the said rollers about 5 their axes to knead the flesh so engaged between them.

3. In a massage device, the combination with a plurality of massage members yieldingly pressed toward each other, and arranged to operate upon flesh engaged between same, of means for imparting vibratory movements to the said members to knead the flesh so engaged.

4. In a massage device, the combination 15 with a pair of massage-rollers, of means for oppositely vibrating same.

5. In a massage device, the combination with a plurality of massage members, and means yieldingly forcing the said members 20 together, of means for oppositely vibrating same.

6. In a massage device, the combination with a plurality of massage-rollers and means for rotating same, of means for oppositely 25 vibrating the rollers about their axes.

7. In a massage device, the combination with a plurality of massage members, of means for imparting a movement of rotation to said members and for also imparting vibratory movements thereto with respect to the 30 said movements of rotation.

8. In a massage device, the combination with a plurality of massage members, and means for yieldingly forcing the same together, of means for imparting a movement of rotation to said members and for also imparting vibratory movements thereto with respect to their said movements of rotation.

9. In a massage device, the combination 40 with a plurality of massage members, of means for imparting a movement of rotation to said members and for also imparting oscillatory movements thereto with respect to the said movements of rotation, the said oscillatory movements of the said members being oppositely timed with respect to each other.

10. In a massage device, the combination with a plurality of massage members, of means for imparting opposite movements of 50 rotation thereto and for also vibrating same with respect to their said movements of rotation.

11. In a massage device, the combination with a plurality of massage members, of 55 means for oppositely rotating same and for also imparting oscillatory movements thereto with respect to their said movements of rotation, the said oscillatory movements of the said members being oppositely timed with 60 respect to each other.

12. In a massage device, the combination with a plurality of massage members, of means for rotating same at a relatively low speed and for also vibrating same at a relatively high speed with respect to their said 65 movements of rotation.

13. In a massage device, the combination with a plurality of massage members, of means for oppositely rotating same at a relatively low speed and for also imparting relatively high-speed vibratory movements thereto with respect to their said movements of rotation.

14. In a massage device, the combination with a plurality of rotary massage members, 75 and a spring for yieldingly forcing the said members together, of means for oppositely vibrating the said members.

15. In a massage device, the combination with a gear-box and a shaft protruding therefrom, of swinging rollers suspended from said shaft, said rollers movable toward and away from each other, and gear connections in said gear-box for driving the said rollers.

16. In a massage device, the combination 85 with a gear-box and a shaft protruding therefrom, of swinging rollers suspended from said shaft, said rollers movable toward and away from each other, and gear connections in said gear-box for rotating said rollers and means 90 for vibrating same.

17. In a massage device, the combination with a gear-box and a handle by which same may be supported, of massage members carried by said gear-box, movable toward and 95 away from each other, and operating elements contained within said gear-box for rotating the said massage members, and also for vibrating them about their axes.

18. In a massage device, the combination 100 with massage members and gearing for rotating same, of means for advancing and retarding said massage members with respect to the gearing driving them.

19. In a massage device, the combination 105 with massage-rollers and gearing for rotating same, of reciprocating means for imparting vibratory movements to the said rollers with respect to their said movements of rotation.

20. In a massage device, the combination 110 with massage-rollers and gearing for rotating same, of a cam and means operated by the cam for imparting vibratory movements to the said rollers with respect to their said movements of rotation.
